UNITED STATES PATENT OFFICE.

CHESTER J. PUGH, OF IDA, LOUISIANA.

DUST AND DIRT CAP.

1,391,692.

Specification of Letters Patent. Patented Sept. 27, 1921.

Application filed March 12, 1921. Serial No. 451,850.

To all whom it may concern:

Be it known that I, CHESTER J. PUGH, a citizen of the United States, residing at Ida, in the county of Caddo and State of Louisiana, have invented certain new and useful Improvements in Dust and Dirt Caps, of which the following is a specification.

This invention relates to dust and dirt protectors for bearings especially of the type employed for the spindle bolts of steering knuckles, and is an improvement on my allowed application filed May 17, 1920, Serial No. 382,060 and the primary object of the present invention is to provide a novel means for absolutely precluding the seeping of all foreign matter between the cap and the part of the steering knuckle engaged by the cap, so as to preclude all possibility of dirt and the like gaining access to the bearing of the spindle bolt.

Another object of the invention is to provide a novel means for holding the improved dust and dirt cap in position on the axle ends, said means for holding the cap in position also forming means for forcing the dust excluding means into intimate engagement with the various parts of the axle end.

With these and other objects in view, the invention consists in the novel arrangement and formation of parts, as will be herein-after more specifically described, claimed and illustrated in the accompanying drawing forming a part of this specification, in which:

35 Figure 1 is a detail fragmentary sectional view of one end of the front axle of a motor vehicle showing the steering knuckle attached thereto and the improved dirt and dust cap in position, the cap also being shown in section for illustrating the novel attaching and dust excluding means carried thereby.

Fig. 2 is an enlarged vertical section taken on the line 2—2 of Fig. 1, showing the improved dust cap holding means and the dust excluding means in operative position.

Fig. 3 is a similar view showing the novel holding means and dust excluding means in inoperative position for permitting the easy and convenient removal or placing of the cap on or off the axle ends, and

Fig. 4 is a bottom plan view of the dust cap with the novel attaching and dust excluding means incorporated therewith.

Referring to the drawings in detail, where-in similar reference characters designate corresponding parts throughout the several views, the letter A indicates the front motor vehicle axle having the usual forked terminal B for the reception of the steering knuckle C. The steering knuckle C and the fork B receives in the usual manner, the spindle bolt D and the bushing E. The spindle bolt D is provided with the usual oil cup F which is provided with the usual 65 spring pressed cap G. This cap G is provided with a flat top as clearly shown in Figs. 1 and 3 of the drawings. The forked end of the axle A includes the upper arm H and the lower arm I and the arms engage 70 the upper and lower ends respectively of the steering knuckle C.

The improved dust cap J is adapted to fit over the oil cup F and the upper end of the spindle bolt D and to engage the upper arm 75 H of the fork B. The dust cap J may be of any desired material, such as sheet metal or the like, and includes the upper oval shaped wall 5, a depending vertical end wall 6, an inclined transversely curved end wall 7, and 80 side walls 8. These side walls 8 are gradually flared toward their lower end and incline inwardly from the end wall 6 toward the end wall 7. It is also preferred that the end wall 6 be curved arcuately so as to conform 85 to the transverse curvature of the spindle bolt D. The wall 7 is also inclined so as to conform to the inclination of the forked end B.

In order to preclude the possibility of dust 90 and the like seeping into the oil cup F, an annular felt pad 9 is provided. This felt pad 9 is secured to the inner surface of the upper wall 5 in any preferred manner, such as by glue, rivets or the like, and is adapted 95 to surround the upper wall or cap G and to frictionally engage the outer surface of the cup F.

In order to provide a tight fit between the walls of the cap J and the sides of the fork 100 B and the knuckle C, a felt strip or the like 11 is provided. This felt strip is of sufficient thickness to be forced into intimate contact with the outer surface of the fork B and the knuckle C. As shown this strip is divided into an inner and outer section 12 and 13 respectively. The inner section 12 is shaped to conform to the general configura-

tion of the fork B, while the section 13 is shaped to conform to the general configuration of the knuckle C. These two sections may be arranged in spaced relation to each other and are adapted to receive therebetween the dust excluder 14, which includes the felt pad 15, and the metal carrier 16. This pad 15 may have one side thereof shaped to conform to the fork B while its opposite side is shaped to conform to the knuckle C and to the section 13 and these surfaces designated by the numeral 17 form substantially a circular opening for entirely surrounding the knuckle C. The metal carrier 16 may be formed in any preferred manner and as shown the same consists of a single strip of metal bent around the felt pad 15, and one end of the same is provided with a resilient catch 18 for engaging one side wall 8 of the cap J. The inner surface of the carrier 16 adjacent to the opposite end of the spring catch 18 is provided with upstanding ears 19 to which is adapted to be pivoted the lower end of the resilient leaf spring 20. The upper end of the leaf spring 20 is riveted or otherwise secured to the opposite end wall as at 21. The spring 20 is bowed intermediate its ends to provide a resilient shoulder 22 for engaging under the upper arm H of the fork B. The dust excluder 14 operates somewhat in the nature of a cam lever, and it can be seen that when the same is in the position shown in Fig. 2, the spring 20 is flexed and forced into tight engagement with the upper arm H of the fork B and when the dust excluder 14 is moved to its inoperative position the spring is moved slightly away from the arm H. This permits the convenient and expeditious removal or placing of the cap J upon the oil cup.

In use of the improved device, the dust excluder 14 is moved to a position shown in Fig. 3 in substantially parallel relation to one top wall 5 and the cap is then pushed down upon the cup F, spindle D and fork B. After the same has moved into position the excluder 14 is moved to a substantially horizontal position, and the spring clip 18 into contact with the opposite end wall 8. This excluder fills up the space intermediate the fork B and the knuckle C and absolutely precludes the possibility of dust seeping into the cap and then around the bearing for the knuckle and bolt D. Further the moving of the dust excluder to its operative position forces the spring 20 into tight engagement with the arm H and absolutely prevents the possibility of the cap being accidentally displaced off of the fork B and spindle bolt D.

From the foregoing description, it can be seen that means has been provided for forming the cap absolutely dust tight and for preventing the accidental displacement thereof from its operative position.

Changes in details may be made without departing from the spirit or scope of this invention; but,

I claim:

1. A dust protector arranged to house the upper end of a spindle bolt, and the upper end of the forked terminal of the front steering knuckle of motor vehicles comprising a housing, a spring catch adapted to detachably hold the housing in position against accidental displacement, and means for moving the catch into operative or inoperative position. 70

2. A dust protector for front axle ends comprising a housing adapted to engage the upper end of the spindle bolt and the upper end of the forked terminal of a front steering knuckle of motor vehicles, a leaf spring carried by the housing for engaging the steering knuckle, and a dust excluding member carried by the cap and arranged for moving the spring into and out of frictional contact with the steering knuckle. 80

3. A dust protector for front axle ends comprising a housing having an upper wall and depending side and end walls, the lower ends of the depending side and end walls being adapted to snugly engage the outer surface of the upper arm of the fork of the axle end and the knuckle and a pivoted dust excluding member carried by the cap adapted to engage the inner surface of the fork and knuckle. 90

4. A dust protector for housing the upper end of a spindle bolt and the upper end of a front steering knuckle of a motor vehicle comprising a housing including end walls for engaging the outer faces of the knuckle and spindle bolt, and a dust excluding member disposed intermediate the end walls for engaging the inner faces of the bolt and steering knuckle. 100

5. A dust protector for front axle ends comprising a housing having an upper wall and depending side walls arranged to engage the upper arm of the fork of the axle end, the knuckle joint and the bearing cap, and an annular dust ring carried by the inner surface of the top wall for engaging around the oil cup. 110

6. A dust and dirt cap for front axle ends of a motor vehicle including an upper wall, depending side and end walls, a spring clip secured at its upper end to one of the walls, and a dust excluding plate hingedly secured to the lower end of said spring adapted to extend transversely across the housing in spaced relation to the end walls thereof. 120

7. A dust and dirt cap for the front axle ends of motor vehicles comprising an upper wall, depending side walls, a spring secured at its upper end to the inner surface of one of the side walls, a transversely extending dust excluding member hingedly connecting 125

the lower end of the spring and adapted to engage the inner faces of the side walls.

8. A dust and dirt cap for the front axle ends of motor vehicles comprising an upper wall, depending side and end walls, a leaf spring secured at its upper end to the inner surface of one of the side walls arranged to frictionally engage the forked end of the axle, a transversely extending plate, a felt

pad carried by the plate, ears carried by the inner surface of the plate and in spaced relation to one end of the plate and hingedly connected to the lower end of the spring, and a spring clip carried by the opposite end of the plate from the pivot ears for engaging the lower edge of one of the side walls.

CHESTER J. PUGH.
